(57) **CLAIM**

I claim the ornamental design for an outsole for a shoe, as shown and described.

DESCRIPTION

FIG. 1 is a bottom view of an outsole for a shoe showing my new design;

FIG. 2 is a bottom perspective view thereof;

FIG. 3 is a left side view thereof;

FIG. 4 is a right side view thereof;

FIG. 5 is a front view thereof;

FIG. 6 is a rear view thereof;

FIG. 7 is a close up bottom perspective view of the area indicated as 7 in FIG. 1; and,

FIG. 8 is a cross sectional view taken along line 8—8 as indicated in FIG. 1.

The broken line partially showing a shoe upper in FIGS. 2–8, and the interior surface in FIG. 8, represents the portion of the design that forms no part of the claim. The parallel broken lines around the periphery of FIGS. 2–6 represent the boundary of the design; with the lines themselves and the areas between them forming no part of the claim.
